UNITED STATES PATENT OFFICE.

HARVEY S. PARDEE, OF CHICAGO, ILLINOIS, ASSIGNOR TO BELLE EVANS PARDEE, OF RAVINIA, ILLINOIS.

ELECTRICALLY-CONTROLLED CARBURETOR.

Application filed April 6, 1922. Serial No. 550,243.

This invention relates to a mixing device, throttle, and solenoid, separately and in conjunction with one another.

Among the several objects of the invention 5 may be noted the provision of a simple and inexpensive mixing device so constructed as to give a suitable mixture of air and liquid fuel throughout varying conditions of speed, load and other factors; the provision of an air 10 and liquid contact apparatus durable in construction and reliable in action, and adapted to withstand mechanical shocks and vibrations without derangement; the provision of an electric solenoid and throttle so constructed 15 as to be in stable equilibrium and at the same time sensitive to slight changes in the current through it; and the provision of a solenoid-controlled mixing and throttle device having some or all of the above features 20 and acting in conjunction with a suitable source of power, such as an engine-driven generator, to maintain within narrow limits the desired characteristic of the system. Other objects will be in part obvious and in 25 part pointed out hereinafter.

The invention accordingly consists of the elements and combinations of elements, features of construction, and arrangements of parts which will be exemplified in the structure hereinafter described and the scope of 30 the application of which will be indicated in the following claims.

In the accompanying drawings, in which is shown one of various possible embodiments 35 of the invention,

Fig. 1 is a section showing the solenoid with mixing device and throttle open;

Fig. 2 is a similar view showing the parts in closed, or substantially closed, position;

Fig. 3 is an elevation of Fig. 1, showing in addition a reservoir and pump associated therewith;

Fig. 4 is a plan of Fig. 3, with parts broken away;

Fig. 5 is an elevation of a throttle member shown in Figs. 1 and 2, showing the arrangement of ports therein; and

Fig. 6 is a wiring diagram.

Similar reference characters indicate corresponding parts throughout the several views of the drawings.

Referring now more particularly to Fig. 1 of the accompanying drawings, there is illustrated a main casting 1 having an intake

opening 2 for air, a delivery port 3 for the 55 mixture, a supply conduit 4 for the liquid fuel, such as gasoline, and an annular member 6 having a passage 15 from the fuel inlet 4 to a jet 17. The member 6 is normally fixed in position. Surrounding the upper portion 60 of the member 6, and movable with respect thereto, is the member 8 (shown in elevation in Fig. 5) having apertures forming the ports 9, and movable either manually or by automatic means such as the solenoid 11 illustrated in Figs. 1 and 2. The solenoid construction is hereinafter described. The member 8 in the present instance acts as a venturi (comprising thus a movable element for effecting, in cooperation with the part 6, 65 constriction of the air passage) and also as the 70 throttle.

The throttle valve as shown in Fig. 1 is open, and in Fig. 2 is closed. By "closed" 75 is meant a position in which the flow of fuel is substantially, but not necessarily completely, shut off. By "open" is meant a position permitting a comparatively free flow of fuel, but not necessarily the position for maximum flow, as the device 8 may have a stroke extending upward beyond the position illustrated in Fig. 1.

In the closed position shown in Fig. 2, in which the member 8 is lowered, the most constricted portions 13 (Fig. 5) of the ports 9 80 are the only portions of the ports that permit communication between the intake 19 and the delivery port 3.

The liquid fuel flows outwardly through the narrow space 17, by suction, the restricted 85 passage between the member 8 and the part 20 of the member 6 acting as a venturi.

The throttle opening at the apertures 9 has an area or section (crosswise of the flow of air or mixture) that varies with movement 90 of the member 8. Air is drawn inwardly to the right through an air inlet 2 and downwardly through the annular space 19 between the members 6 and 8.

In Fig. 2, as indicated above, the member 95 100 8 is shown in closed position, with the ports 9 nearly cut off. The point where the fuel suction takes place, that is, the annular space between ports 20 and 8, is also reduced in area causing a comparatively high velocity and consequently an increased suction past the jet opening.

As the member 8 moves upward from this

Fig. 2 (closed) position the mixture is throttled to a progressively less extent (that is, the flow is progressively increased) by the progressive increase of the size of the ports 9 at the edge 10. In the construction of the present invention, the suction at the jet is, unlike a fixed-venturi construction, adjusted so as to give a constant ratio of air to fluid fuel under varying rates of flow. The throttling is done primarily at the edge 10 of the ports and not at the variable venturi. The venturi is for the purpose of furnishing and regulating the suction to draw the fuel.

With the present invention the mixture ratio is maintained at the desired value under widely varying load and speed conditions of the engine, since the proper ratio of suction to rate of flow of air is effected automatically for the various working positions of the member 8.

Adjustment of richness of mixture may be made by changing the setting of the needle valve 21, shown in Fig. 4. The needle valve is mounted in the path of the liquid fuel from the chamber 25 to the supply conduit 4, and may be of any suitable construction. Liquid fuel is supplied to the chamber 25 by means of a pump 62 adapted to draw liquid from a reservoir 64. An overflow pipe 66 in the chamber 25 limits the height of liquid therein.

A preferred way of determining a suitable shape for the ports 9 experimentally is to start the engine with ports that are at least large enough to deliver a sufficient quantity of mixture for full power when wide open. The needle valve is then adjusted so that power is delivered by the engine at maximum fuel efficiency when this member 8 is wide open. Then by successive adjustments in the vertical positioning of the member 8 and by minor operations of cutting away the ports, with such further changes in the setting of the needle valve as may be needed, the proper shape of ports and relations of ports to edge 10 may be readily found for enabling maximum power or maximum engine efficiency to be obtained at all positions of the member 8, without changing the setting of the needle valve for varying load conditions. With certain hydrocarbons such as gasoline, the most efficient mixture is not widely different from the mixture that gives maximum power; so that when the needle valve is so adjusted for any given setting of the venturi and throttle as to give maximum power, then the most efficient mixture is approximately obtained. It is thus not difficult to ascertain the proportioning of ports and position of the member 8 for approximately the best working conditions. The determination may be made more exactly by measuring the air and fuel separately, if desired.

The member 8 may be moved vertically by any convenient controlling means. A pre-

ferred form of control is an electric solenoid, such as solenoid 11, illustrated in Figs. 1 and 2.

The solenoid may be controlled by a manually or automatically operated rheostat (not shown) or, in installations such as an engine-driven electric generating plant (Fig. 6), the solenoid may be connected in various ways, such as across the generator G (solid lines in Fig. 6) or to its work circuit L (dotted lines in Fig. 6) and thus move in accordance with variations in generator voltage or other variable factor. For example, if the solenoid is connected across the generator voltage (solid lines in Fig. 6), an increase in voltage causes increased magnetic effect in the solenoid, lowering the solenoid core 27 and moving the member 8 downward toward its closed position shown in Fig. 2, thereby decreasing the fuel supply to the engine and neutralizing or preventing the incipient increase in voltage. Similarly, any tendency of the generator voltage to decrease is met by upward movement produced by a spring 43 and lever 44, of the solenoid core or element 27 and member 8, sufficient to restore or maintain the normal value of the voltage.

The solenoid per se preferably comprises a bobbin 29 on which the coils 31, 32 are wound, a shell 33 of magnetic material surrounding the coils and provided with an inwardly extending annular rib 35 at a point above the coils, this rib registering with the disc-shape flanged portion 37 of the core 27, with a suitable air-gap 39 between rib and flange. The rib and flange are preferably in registry, that is, juxtaposed, when the core is at or near its uppermost position (Fig. 1), though this relation of rib and flange may be varied to meet varying service requirements, without departing from the spirit or scope of the present invention. In the lowered position of the core (Fig. 2) the flange is shown as below the plane of the rib, causing the magnetic attraction between the two to tend to raise the core. This is in opposition to the downward pull caused by the lines of force passing from the core to the magnetic plug or stop 41. The increased air-gap between rib and flange also tends to weaken the downward pull on the core.

A third factor affecting the movement of the core is the spring 43, mounted, in this instance, on the casting 1 and adapted to be flexed by a bell-crank 44 connected to an anti-friction pin 45 mounted in a vertically reciprocating extension 46 pinned as at 48 upon the upper end of the solenoid core 49. The extension 46 is in turn secured to the annular member 8 by means of the pin 51 shown in Figs. 1 and 2. During the downward movement of the member 8 and solenoid core from the open position shown in Fig. 1 to the closed position shown in Fig. 2, the spring

43 abuts successively against adjustable stops 53. This abutting of the spring against the successive stops varies the effective leverage of the spring, and causes the spring to offer 5 progressively increased resistance to the downward movement of the core. The curve of spring force and core position shows a materially increasing spring force as the core moves downward. Various arrangements of springs may be employed, depending 10 upon what shape of curve is wanted in order to get the desired results. In some instances no spring at all is needed.

With the core in its upper position shown 15 in Fig. 1, the downward movement is effected by the attraction on the core. As the core moves downward, this attraction increases. At the same time the upward attraction between rib and flange opposes the downward 20 pull on the core, and the weakening effect of the increasing air-gap 39 tends to reduce the total magnetic flux below what it would otherwise be and therefore likewise the downward pull.

25 A guide 47 may be provided to keep the core in a central position with respect to the bobbin.

The apparatus of Fig. 1 is preferably so proportioned that the moving parts are always in stable equilibrium throughout the working stroke, with no tendency to move in either direction save as required by changing strength of the current in the solenoid coils. By working stroke is meant the normal travel 30 during the operation of the parts 27, 37, 46 and 8. The venturi and throttle device, either with or without the solenoid, is preferably balanced, that is, it is unaffected, when moving or at rest, by the flow of mixture, and is sensitive to slight increases or decreases of 35 the force controlling its movement. The device reaches its position of equilibrium in each instance without hunting, owing to the substantial force tending to bring it to such 40 position whenever the condition of equilibrium has been disturbed from any cause. Hunting may be avoided by having the algebraic increase of mechanical force (spring force plus weight of moving parts) with 45 downwardly moving core, greater than the corresponding algebraic increase of magnetic pull with downward movement of the core throughout the working part of the stroke. Furthermore, by having the magnetic circuit 50 complete except for small air gaps between rib and flange and between core and plug, the solenoid has a high magnetic efficiency, which means compactness and economy of construction and operation.

55 The solenoid has preferably two windings 31, 32, as above noted. These are respectively shunt and series windings. A preferred type of wiring is shown in Fig. 6, wherein the shunt winding 31 is connected to the terminals of the engine-driven generator G and

the series winding 32 is connected to carry generator current, the series winding opposing the shunt winding and weakening the solenoid pull when the load increases. This makes it possible to have a substantially flat 70 voltage characteristic. Or, the voltage may be caused to increase with increase of load, or any other desired characteristic of similar nature may be obtained by varying the ratio 75 of series and shunt turns.

The automatic choke device shown at the top of the solenoid in Figs. 1 and 2 may be dispensed with if desired. This device comprises a solenoid having a magnetic shell 69, bobbin 71, winding 73, and movable core 75. 80 The lower end of the core 75 acts as the upper surface of the air inlet passage 79. The solenoid winding 73 is preferably connected across the generator mains, as indicated in Fig. 6. The winding 73 is thus de-energized 85 when the generator G is being started. This means that during the starting of the engine the core 75 is in its lowermost position, shown in dotted lines in Fig. 1, thereby shutting off part of the air supply and giving an increased 90 suction during starting. In other words, this construction affords an automatic choke during starting.

If desired, a conduit 81 may extend from the crank-case (not shown) of the engine 95 (not shown) into the air inlet 2. The suction in the air inlet induces a suction in the conduit 81, thereby providing what may be termed an "oil breather" to draw oil and the other vapors from the crank-case. In the 100 present instance the vapors are drawn into the engine, where the lubrication afforded by the oil may be of value. This operation serves to rid the room in which the apparatus is located, of the odors of such vapors. 105

The level of the top of the overflow pipe 66 (Fig. 3) determines the head on the gasoline feed. This level is preferably a little below the level of the jet 17, so that suction is required at the jet to bring fuel from the 110 chamber 25 to the jet.

If desired, steam (if available) may be admitted through the conduit 93, together with air through the conduit 95, into a passage 97 controlled by an adjustable needle 115 valve 99, so that steam may be supplied to the air passage 79 along with the air that enters this passage through the inlet tube. It is noted that such steam is subject to the choking effect of the core 75. 120

From the above it will be seen that in the apparatus of the present invention the several objects above noted are attained and other advantageous results secured.

As various possible embodiments might be made of the above invention and as various changes might be made in the embodiment above set forth without departing from the spirit or scope of this invention, it is to be understood that all matter herein set forth 125

or shown in the accompanying drawings is to be interpreted as illustrative and not in a limiting sense.

I claim:

- 5 1. In apparatus of the class described, in combination, a movable venturi and throttle, and means for operating the same, said means comprising a solenoid, a series of stops, and a spring adapted to engage the stops to oppose the movement of the solenoid core.
- 10 2. In apparatus of the class described, in combination, a movable venturi, and means for operating said venturi, said means comprising a solenoid having a movable element, a series of stops, and resilient means associated with said movable element adapted to engage said stops successively to oppose the movement of the movable element of the solenoid.
- 15 3. In apparatus of the class described, in combination, a needle valve, an inlet air passage, a fixed member apertured to receive fuel from a source of supply through the needle valve and said fixed member being adapted to eject the fuel into said air passage to form a combustible mixture with said air, a vertically movable member having a port to permit flow of said combustible mixture of fuel and air from said air passage, a solenoid for operating said movable member, and a spring associated with said solenoid abutting successive stops to offer increasing resistance to movement of said movable member.
- 20 4. In apparatus of the class described, in combination, a valve adapted to control a fuel supply, an inlet air passage, a fixed member apertured to receive fuel from a source of supply through said valve, said fixed member being adapted to eject said fuel into the air passage to form a combustible mixture, a movable member adapted to control the flow of said combustible mixture from said air passage, and a solenoid for operating said movable member, said solenoid having means associated therewith adapted to offer increasing resistance to the movement of said second member as the solenoid moves said second member to close.
- 25 5. In apparatus of the class described, in combination, a movable venturi and throttle member, and means for operating the same, said means comprising a solenoid having a core adapted to move said member and means associated with said solenoid core adapted to increasingly oppose the movement of the solenoid core as said core becomes increas-

ingly effective in its movement of said member.

6. In apparatus of the class described, in combination, a movable throttle member, and means for operating the same, said means comprising a solenoid having a core adapted to move said member, and means associated with the solenoid adapted to maintain the throttle member in equilibrium at different points in its range of movement and to control said movement in a predetermined manner, said last-named means comprising a magnetic shell on the solenoid, a rib on said shell, a flange on said core cooperating with said rib, a spring adapted to oppose the movement of the solenoid core and a series of stops abutted by said spring.

7. In apparatus of the class described, in combination, a movable venturi and throttle member, and means for operating the same, said means comprising a solenoid having a core adapted to move said member, and means associated with the solenoid adapted to maintain the throttle in equilibrium at different points in its range of movement and to control said movement in a predetermined manner, said last-named means comprising a magnetic rib in the magnetic circuit of said solenoid, means on said core movably cooperating with said rib, and means for increasingly resisting the movement of the solenoid core as said movement increases.

8. In apparatus of the class described, in combination, a member adapted to receive fuel from a source of supply, having a passage for fuel therein, a throttle member surrounding said first-named member, an air inlet for admitting air to the space between said members, said throttle member controlling the flow of fuel mixture from said space to a discharge conduit, means whereby air passing through the throttle member draws fuel from said passage, the parts being proportioned to give proper mixture in the several positions of said throttle member and means for automatically operating said throttle member comprising a solenoid having a core movable with said throttle member, a magnetic shell for the solenoid, a rib extending from said shell and a flange on said core registering with said rib when the throttle is in its open position.

In testimony whereof, I have signed my name to this specification this 28th day of March, 1922.

HARVEY S. PARDEE.
